UNITED STATES PATENT OFFICE

ERICK J. AJAX, OF MINNEAPOLIS, MINNESOTA, ASSIGNOR TO DOMINION ELECTRICAL
MANUFACTURING COMPANY, A CORPORATION OF MINNESOTA

DESIGN FOR A WAFFLE IRON OR SIMILAR ARTICLE

Application filed August 18, 1930. Serial No. 36,700. Term of patent 3½ years.

To all whom it may concern:

Be it known that I, ERICK J. AJAX, a citizen of the United States, residing at Minneapolis, in the county of Hennepin and State of Minnesota, have invented a new, original, and ornamental Design for Waffle Iron or Similar Article, of which the following is a specification, reference being had to the accompanying drawing, forming part thereof, wherein:

Fig. 1 is a perspective view of a waffle iron or similar article showing my new design;

Fig. 2 is a plan view of the same, and

Fig. 3 is a cross sectional perspective view through the fluting at the top of said waffle iron or similar article.

What I claim is:

The ornamental design for a waffle iron or similar article substantially as shown.

ERICK J. AJAX.
